PICKET FENCE

Hugh O. Wolfe and Carl E. Kessler, Mineral Wells, Tex.; said Wolfe assignor to said Kessler

Application May 18, 1956, Serial No. 585,857

6 Claims. (Cl. 256—22)

This invention relates to picket fences or similar structures wherein narrow members are arranged in parallel relation to define a plane.

Generally, the invention is directed to an arrangement of parallel slats or pickets of spring sheet metal or other flat resilient material having notches in their side edges for engaging corresponding recesses in supported transverse rails. This application is a continuation in part of our copending application, Serial No. 430,254, filed May 17, 1954, now abandoned.

An object of the invention is to provide a picket assembly wherein the pickets may be expeditiously locked and firmly secured in their supporting rails without the use of separate fastening means.

Another object of the invention is to provide a fence incorporating the described picket assembly and which fence is capable of being readily erected on either level or sloping terrain.

A further object of the invention is to provide a picket fence wherein the pickets are of deformable sheet material and wherein pickets of uniform length are readily located to define straight lines along the upper and lower edges thereof even though the distance between the parallel supporting rails may vary, as between rails mounted at a given distance on vertical posts where the rails are over level terrain and where the rails are secured at the same distance on vertical posts but over sloped terrain.

A further object of the invention is to provide, in a fence of the described character, a rail construction which does not require bolt receiving holes for attaching the rails to fence posts.

A still further object of the invention is to provide a picket fence assembly capable of being manufactured economically, and one which may be readily assembled by unskilled workmen.

These and other objects of the invention will become apparent from the following description and the accompanying drawing, wherein:

Figure 1 is a fragmentary length of fence constructed and assembled in accordance with the invention.

Figure 2 is an end elevation of the fragmentary length of fence shown in Figure 1.

Figure 3 is a fragmentary front elevation on an enlarged scale of the upper end of a preferred picket construction.

Figure 4 is a top plan view on a further enlarged scale showing a picket in accordance with the invention secured to a transverse supporting rail.

Figure 5 is a view similar to Figure 4, but showing the picket partially installed.

Figure 6 is a perspective view of the picket and rail construction illustrated in Figures 4 and 5, and showing a simple hand tool which may be employed for installing the pickets.

Figure 7 is a fragmentary elevation of the upper portion of a length of fence, as shown in Figure 1, but where in the rail is sloped as occurs when the fence is installed on sloping terrain.

2

Figure 8 is a top plan view similar to Figures 4 and 5, but showing a modified form of the invention wherein the edges of the pickets are installed in overlapping relation.

5 Figure 9 is a top plan view of a further modified form of the invention wherein the edges of the pickets are inwardly directed relative to the centers thereof, and

10 Figure 10 is a top plan view showing a staggered arrangement of pickets on opposite sides of a rail so as to provide a ventilated slat or picket arrangement, yet one which prevents a direct line of sight therethrough.

Figure 11 is a fragmentary front elevation of a picket as illustrated in Figure 3, but showing an arrangement of notches in opposite edges of the picket.

15 In the exemplary form of the invention shown in Figures 1 through 7, posts 11 of angle stock are anchored in the ground with front sides 12 thereof parallel with the direction of the fence to be erected and with the remaining sides 13 rearwardly projected. The edges 14 of 20 the rearwardly projecting sides 13 may be downwardly and outwardly sloped, as at 14, to reduce the weight and cost and yet provide the necessary strength against bending.

The posts 11 are provided with upper, lower and intermediate horizontal rails 15 which are preferably made of angle stock and are arranged so that corresponding upper sides or flanges 16 project forwardly and with their remaining sides 17 vertical and against the forwardly facing sides 12 of the posts. The rails 15 are detachably secured in place by means of relatively flat U-shaped clamps 18 and held in place by means of bolts 19 positioned therethrough and through holes, not numbered, in the forward side 12 of the posts 11. Nuts 20 on the bolts 19, and positioned against the rear face of the front sides 12 of the posts, are preferably of the self-locking type. As shown in Figures 1 and 2, the lower edge of the vertical sides 17 of the rails 15 may rest on the bolts 19 for initially locating and positioning the rails relative to the earth's surface. When required, the clamps 18 30 may be adjusted to permit variations in the locations of the rails 15 on the posts.

40 Spaced pairs of slotted recesses are divergently disposed in the extending edges of the upper rail sides 16, and which pairs of recesses are spaced to receive the side edges 22 of the pickets 23. The pickets 23 are generally 45 arcuate in transverse section, but it is to be understood that the term "arcuately" as used herein includes transverse sections wherein the longitudinal center portion of the picket may be flat, corrugated or of some other geometrical shape wherein the edges thereof define angles at least generally conforming with the angles of the diverging pairs of slotted recesses 21 at the time the pickets are installed. The distance across each picket, side edge 22 to side edge 22, is normally greater than the distance between the remote ends of the corresponding pair of slotted recesses 21 in which the picket is received. Each picket 23 is provided with a notch 24 in at least one side edge 22 thereof for interfitting with an inner end of a slotted recess 21 in a projecting rail side 50 55 60 65 70 75 80 85 90 95 100 lapping, but which arrangement embodies the novel features of the invention. The pickets 25 have the same general transverse configuration as the described pickets 23 or referred to variations thereof, but one side is outwardly curved, as at 26, to be received within an arcuate slotted recess 27 in the forward side of rails 28. The remaining edge 29 of each picket 25 is received in a straight or substantially straight slotted recess 30, also in the forward edge of the rail 28. Pairs of arcuate recesses 27 and companion recesses 30 are generally disposed in diverging relation for receiving edges 26 and 29 of the pickets 25. As described in connection with the first form of the invention, the pickets 25 are of spring sheet material and are normally wider than the distance across the outer limits of the respective pairs of recesses 27 and 30.

The form of the invention shown in Figure 10 illustrates an arrangement of pickets 23 similar to the one shown and described in connection with Figures 1 through 7. The pickets 23 are arranged in staggered relation on opposite sides of rails 35, and the pairs of diverging slotted recesses therein correspond with the previously described slotted recesses 21. The picket edges 22 on one side of the rails 35 overlap the edges 22 of the pickets 23 on the other side, thus providing a ventilated surface which prevents a line of sight therethrough.

As shown in Figure 6, a simple hand tool 37 may be used for installing and locking the pickets 23 and 25 in pairs of slotted recesses 21 in the slotted recesses 27 and 30 in the rails 28. The tool shown includes pivoted handles 38 and integral jaws 39. The ends of the jaws are inwardly directed to provide hooks 40 for engaging and compressing the edges 22 of the pickets 23. It is to be understood that other suitable means may be used for compressing the pickets 23 within the scope and spirit of the invention. It is pointed out that when the pickets 25 having arcuate edges 26 along one side thereof are installed in the arcuate recesses 27, that side of the picket is installed first and the remaining side 29 is positioned in the opposite slot 30 after the curved edge is in place.

In the form of the invention shown in Figure 9, the pickets 33, which are generally arcuate in transverse section, are spread apart so that the free edges 34 may engage the converging pairs of recesses 31. Notches such as 24, may be provided in all forms of the pickets 23 and

25 along the free edges thereof for engaging their cooperative slotted recesses 21, 27, 30 or 36, as the case may be. Also, in all forms of the invention the spring action of the pickets is employed for holding and securing the same in place.

The invention is not limited to the exemplary constructions herein shown and described, but may be varied in various ways within the scope of the appended claims.

What is claimed is:

1. A knock-down fence structure comprising a plurality of longitudinally spaced vertical posts, upper and lower rails removably connected to the posts, said rails having generally horizontal flanges projecting laterally outwardly therefrom and having free edges, said flanges being provided with longitudinally spaced pairs of slots opening through said free edges, and a plurality of vertically disposed pickets of generally channel form, said pickets being of spring sheet material having their opposed free sides frictionally engaged within said slots.
2. A fence structure as defined in claim 1 and wherein said spaced pairs of slots in said flanges are divergently disposed relative to and along corresponding edges thereof.
3. A fence structure as defined in claim 1 and wherein said spaced pairs of slots in said flanges are convergently disposed relative to and along corresponding edges thereof.
4. In a fence structure as defined in claim 1, at least one notch in one side edge of each said picket adapted to engage at least one slot in one of said flanges.
5. A fence structure as defined in claim 1 and wherein clamps are mounted on said posts and frictionally engage said rails.
6. A fence structure as defined in claim 2 and wherein corresponding slots in said flanges are of arcuate shape and wherein corresponding sides of said pickets are arcuate and are received in said arcuate slots.
